UNITED STATES PATENT OFFICE.

JOSEPH L. CAUSEY, OF KANSAS CITY, MISSOURI, ASSIGNOR TO NORTH AMERICAN BISCUIT COMPANY, OF KANSAS CITY, MISSOURI, A CORPORATION OF NEW JERSEY.

OIL-BURNER.

No. 874,488.

Specification of Letters Patent.

Patented Dec. 24, 1907.

Application filed May 19, 1906. Serial No. 317,761.

To all whom it may concern:

Be it known that I, JOSEPH L. CAUSEY, a citizen of the United States, residing at Kansas City, in the county of Jackson and State of Missouri, have invented certain new and useful Improvements in Oil-Burners, of which the following is a specification.

This invention relates to oil burners and while designed more especially for use in 10 bake ovens and furnaces may of course be used wherever adaptable, and my object is to produce an oil burner which operates efficiently and reliably, which can be regulated in its heat developing capacity and 15 with which combustion takes place with comparatively little sound.

With this object in view and others as hereinafter explained, the invention consists in certain novel and peculiar features of 20 construction and organization as hereinafter described and claimed; and in order that it may be fully understood reference is to be had to the accompanying drawing, in which—

Figure 1, is a horizontal section of a burner 25 embodying my invention, taken on the line I—I of Fig. 3. Fig. 2, is a side view of a portion of the burner. Fig. 3, is a cross section taken on the line III—III of Fig. 1. Fig. 4, is a cross section on the line IV—IV of Fig. 1. 30 Fig. 5, is a side view of the extremity of the burner-tube extension. Fig. 6, is a section on the line VI—VI of Fig. 7, showing a modified construction of the front end of the burner. Fig. 7, is a horizontal section on the 35 line VII—VII of Fig. 6.

In the description and claims the word fluid is intended to cover air or steam as distinguished from oil, as either of the first-named fluids may be employed with satisfactory results.

In the said drawings, 1 indicates the body portion of the burner, the same being of cylindrical form and externally threaded forward and rearward of the laterally projecting internally threaded bosses 2 and 3. The body portion is provided with a reduced extension 4 having its front end diametrically enlarged at 5, and provided with a plurality of nicks or slits 6, which extend obliquely for 45 a purpose hereinafter explained. The burner is provided with a central bore or passage 7 which extends through the extension and is threaded at its rear end at 8.

9 indicates a pipe screwed into boss 2, and adapted to discharge air under pressure into

the rear end of fluid passage 10 formed around but separated from the contiguous portion of the oil passage 7, an oil pipe 11 being screwed into boss 3 to supply oil to passage 7 through the small connecting passage 12.

The valve for controlling the passage of oil to the burner, comprises a threaded portion 13 engaging threads 8, a portion 14 and a reduced front portion 15, portion 14 fitting snugly in the passage 7 and the reduced portion loosely therein so that a circular film of oil shall be discharged from the front end of the bore or passage and thus mix more readily with the fluid as hereinafter explained. The valve is provided with a handle 16 at its 70 rear end by which it may be screwed forward to cause portion 14 to partially or wholly cover the hole or passage 12, or said valve may be moved further forward for a purpose which hereinafter appears.

17 indicates a packing nut mounted on the rear end of the burner and having its front end dished and opposite the dished rear side of a nut 18 also mounted on the burner, a suitable packing 19 being clamped between said 80 dished surfaces to make the joint absolutely liquid tight.

20 indicates the burner cap screwed upon the front end of the body portion of the burner, and provided with a burner orifice 21 85 in its front end, said cap fitting snugly on the enlargement 5 so that the latter shall constitute a skeleton partition between the front portion of the cap passage—which portion constitutes the mixing chamber—and the 90 rear portion of said cap passage, said last-named portion communicating with and forming a continuation of fluid passage 10. Rearward of the cap, a nut 22 is mounted on the body portion and is dished in its front 95 side to receive a packing 23 clamped therein by the rear end of the cap, this packing like packing 19 and the packing of the packing nut, being of mineral wool or other non-combustible material.

With the parts arranged as shown in Fig. 1, the oil may pass through passage 7 and the fluid through passage 10, said fluid being under considerable pressure in order that by passing through the inclined nicks or slits it 105 shall be caused to whirl spirally in the mixing chamber and thus effect practically instantaneous vaporization of the oil as the latter enters such chamber, the combustible mixture thus formed being discharged with 110

considerable force through the orifice 21 where it is ignited by a lighted match or taper and burns fiercely and with but little noise. To reduce the flame the valve is 5 moved forward to partially close passage 12, and if it is desired to cut off the oil supply entirely, the valve is screwed forward a sufficient distance to effect such purpose. This can be accomplished without cutting off the 10 supply of the fluid which should continue to pass through the burner where used in an oven or furnace (particularly a candy furnace) to, in effect, insulate the burner and prevent it from melting under the intense 15 heat of the refractory material usually found in such ovens or furnaces. Ordinarily the fluid is permitted to pass through the burner until the temperature of the oven or furnace falls sufficiently to eliminate all danger of injury to the burner. The attendant then 20 screws the valve forward until it projects through the burner orifice to prevent the latter becoming clogged with asphaltum or other residual properties of the oil.

25 For use in ovens for baking crackers, cakes and like articles, it is preferred to provide the burner with a long narrow burner orifice arranged horizontally so as to produce a horizontal fan-like flame.

30 In Figs. 6 and 7, the burner cap is provided with a slot 24, and with longitudinal guide lugs 25, above and below the slot. 26 indicates a slide plate mounted between said guide lugs and provided with a T-shaped 35 notch in its rear edge and extending into said notch is the front end of a valve rod 15^a corresponding in function and general construction to the valve of Fig. 1, the front end of said rod terminating in a head 28 journaled 40 in the stem portion of the T-shaped slot 27, so that when said rod is turned to move forward or rearward, it shall cause the slide plate 26 to move in the same direction, it being understood that said valve rod can be 45 moved forward sufficiently to project the slide plate through the slot 24 and thus prevent any possibility of the latter becoming clogged up, as explained with reference to orifice 21.

50 From the above description it will be apparent that I have produced a burner possessing the features of advantage enumerated as desirable in the statement of the object of the invention and I wish it to be understood 55 that I do not desire to be restricted to the ex-

act details of construction shown and described as various changes in the form, proportion, detail construction and arrangement of the parts may be made without departing from the principle of construction involved.

Having thus described the invention what I claim as new and desire to secure by Letters Patent, is:

1. A burner comprising a body portion 65 provided with an oil passage, and a reduced extension through which said passage continues and provided also with a fluid passage exterior to said extension and with tubular bosses communicating respectively with the 70 oil passage and the fluid passage a packing nut on the rear end of the body portion, an enlargement at the front end of the reduced extension provided with nicks or slits, a cap fitting around said reduced extension and 75 snugly engaging the enlargement thereof and screwed at its rear end to the body portion of the burner and provided at its front end with a jet orifice, and a valve comprising a threaded portion extending through said 80 packing nut and bearing a threaded relation with said oil passage, a non-threaded portion having a liquid-tight joint with the oil passage and adapted to cut off communication between the same and the tubular-boss passage 85 communicating therewith, and a reduced extension fitting loosely in the forward portion of said oil passage and adapted to project through the jet orifice and cut off the supply of fluid therethrough. 90

2. A burner comprising a body having a reduced extension and provided with oil and fluid passages, the oil passage extending through the extension and the fluid passage extending outside the extension, a cap secured to the body and inclosing the extension and provided with a jet orifice in alignment with said extension, a skeleton partition within the cap around the end of the extension, and a valve arranged in and movable through the extension to successively cut off the flow of oil through the extension and to close the said jet orifice. 95

In testimony whereof I affix my signature, in the presence of two witnesses.

JOSEPH L. CAUSEY.
